(57) **CLAIM**

The ornamental design for a pad for clean application of dermatological or cosmetic products to the skin, as shown and described.

DESCRIPTION

FIG. 1 is a front, bottom, and right side perspective view of a pad for clean application of dermatological or cosmetic products to the skin showing my new design;

FIG. 2 is a rear, bottom, and right side perspective view thereof;

FIG. 3 is a bottom plan view thereof;

FIG. 4 is a top plan view thereof;

FIG. 5 is a right side elevational view thereof, the left side elevational view being a mirror image of the right side elevational view shown;

FIG. 6 is a front elevational view thereof;

FIG. 7 is a rear elevational view thereof; and,

FIG. 8 is a front elevational view thereof, with a cover of the pad partially removed.
